GEORGE W. BINGHAM, OF NEW YORK, N. Y.

SPANGLE CUTTING AND ATTACHING MACHINE.

940,229.

Specification of Letters Patent.

Patented Nov. 16, 1909.

Application filed June 15, 1906, Serial No. 321,893. Renewed September 11, 1909. Serial No. 517,287.

To all whom it may concern:

Be it known that I, GEORGE W. BINGHAM, a citizen of the United States, residing at 266 West Eleventh street, New York city, in the county of New York and State of New York, have invented certain new and useful Improvements in Spangle Cutting and Attaching Machines, of which the following is a specification, reference being had 10 therein to the accompanying drawing.

This invention is a machine for making spangles or the like and attaching them to scarfs, neckwear, regalia, etc.

The object of the invention is to provide 15 a machine of this character which will be simple and comparatively inexpensive in construction, convenient and easy to operate, and very effective for the purpose intended.

20 Further objects and advantages of the invention and the structural features by means of which they are attained, will be made clear by an examination of the following specification, taken in connection with 25 the accompanying drawings, in which,

Figure 1 is a vertical longitudinal sectional view through the machine; Figs. 2 and 3 are vertical transverse sectional views taken respectively on the planes indicated 30 by the lines 2—2 and 3—3 in Fig. 1; Fig. 4 is a detail horizontal sectional view; Fig. 5 is a detail view showing the mutilated or intermittent gears; Figs. 6 and 7 are detail views of the punches and dies showing the 35 operation of the machine; and Figs. 8, 9, and 10 are views showing the spangles that are made and attached by the machine. Figs. 11, 12 and 13 are views similar to Fig. 2 but showing the several cranks in their 40 varying positions.

The embodiment of the invention shown in the drawings, comprises two coacting rotary dies 1, 2, a multiple punch 3 to coact with the same, a spring die 4 and a second 45 punch 5 to coact with said spring die and with one of said rotary dies. Each of the latter is in the form of a hollow or recessed cylinder having in its periphery, adjacent to its open end, die apertures or openings disposed, preferably, at diametrically 50 opposite points. The closed ends of these cylinders have projecting from them, concentric trunnions or shafts 6 which are journaled to rotate in a bearing 7 depending 55 from a bed plate 8, or other suitable support. Said die cylinders are superposed in

vertical alinement, so that the uppermost point of the upper one 2 is flush with the top of the bed plate and disposed in an opening in the same, and so that their peripheries or outer faces contact as they are rotated. They are caused to rotate together by means of intermeshing gears 9, 10, secured to the cylinders by bolts 10^a. The die openings in these cylinders may be of 60 any size and shape according to the size and shape of the spangle to be made and attached by the machine, but, in the present embodiment of the invention, the openings 11 in the lower cylinder 1 are shaped so as 65 to cut the spangle blank 12 shown in Fig. 8 of the drawings. The openings 13 in the upper cylinder 2 are smaller than the openings 11 and correspond in shape to the finished spangle. As shown, the blank 12 is 70 in the form of a parallelogram and is adapted to be made into a spangle of rectangular form, by bending the points or prongs 14, at the diagonally opposite corners of its body portion 15, over upon the 75 latter, as clearly shown in Figs. 9 and 10.

The multiple punch 3 is mounted for vertical reciprocating movement in a guide 17 depending from the bed plate 8. Said punch 3 comprises a body portion which 80 slides in the guide 17 and from which projects three punches 18, 19, 20. The lower punch 18 is disposed below the cylinder 1 and is adapted to cut the blanks 12 from a strip of metal 21 which is fed between said 85 punch and cylinder in any suitable manner. The intermediate punch 19 is disposed within the cylinder 1 and is adapted to feed the blanks 12 from the openings 11 in the cylinder 1 into the openings 13 in the cylinder 90 2 and at the same time bend the prongs or points 14 of said blanks at right angles to their bodies 15. The upper punch 20 is disposed within the cylinder 2 and is adapted to force the partially bent spangles from 95 the openings 13, so that their prongs 14 pass through the fabric or other material upon which the spangles are secured by the machine. As the prongs of the spangles are thus forced through the fabric, they enter 100 between the jaws 21 of the spring die 4 and the reciprocating punch 5, which latter is disposed between said jaws. The spring die 4 depends from a supporting arm 22 provided upon the top of the bed plate 8 and 105 is preferably formed from a single piece of metal by dividing and shaping it to pro-

vide the resilient jaws 21. The latter spring normally together so as to bend the prongs 14 of the spangles inwardly, and they are forced apart by the punch 5 as it 5 enters between the oppositely inclined portions 23 of the inner faces of said jaws. Projections 24 are formed at the lower ends of the inclines 23 so that the jaws will be spaced from the opposite faces of the punch 10 5 to permit the prongs 14 of the spangles to enter between them as previously stated. The punch 5 is adapted to be twice reciprocated to each half rotation of the cylinder 2, so that as the punch is elevated or raised 15 the first time, the jaws 21, owing to their resiliency, will spring together and bend the prongs 14 inwardly, and as said punch descends the second time, it will mash said prongs down flat against the bottom or 20 under face of the fabric through which they extend. The punch 5, as shown, is secured in a slot in the lower end of a bar 25 which is disposed vertically and is mounted to slide through bearings 26 formed on the 25 outer end or head of the supporting arm 22.

Any suitable means may be employed for intermittently rotating the dies or cylinders 1, 2, intermittently reciprocating the multiple punch 3, and reciprocating the second 30 punch 5, but I preferably mount, in suitable bearings beneath the bed plate, a main shaft 27 which may be rotated in any suitable manner and from which said punches and dies are driven. An intermittent reciprocating motion is imparted to the punch 3 by means of a cam 28 which is secured upon the shaft 27 and is in the form of a circular plate or disk provided in one of its faces with an irregular shaped cam groove 29 35 adapted to receive an anti-friction roller 30 carried by the punch 3. An intermittent rotary motion is imparted to the dies 1, 2 by providing beneath the bed plate 8, in the horizontal plane of the shaft 27, a counter-shaft 31 and connecting the latter to the shaft 27 by mutilated gears 32, 33, the former of which is provided with two teeth 40 mutilated to the extent of having one half of each tooth cut away, and the latter 45 of which is provided with a disk portion 41 of one half the thickness of the teeth 42, as clearly shown in Fig. 5. Thus as the drive-shaft 27 is continuously rotated an intermittent rotary motion will be imparted 50 to the shaft 31. The motion of the latter is imparted to the rotary dies by means of a gear 34 which is secured upon the shaft 31 and meshes with the gear 9 on the die or cylinder 2. The punch 5 is continuously 55 reciprocated by mounting in the arm 22, which is preferably hollow, a shaft 35 on which are crank-arms 36, 37. The arm 36 is connected by a rod or link 38 to a crank 39 on the drive-shaft 27, and the arm 37 is 60 connected by a rod or link 40 to the bar 25

65

of the punch 5. Owing to the fact that the crank 39 has a smaller throw than the crank-arm 36, the shaft 35 will be oscillated while the shaft 27 is rotated.

The operation and advantages of the invention will be readily understood from the foregoing detail description, taken in connection with the accompanying drawings and the following brief statement. The material upon which the spangles are to be secured, is supported upon the bed plate and guided by the operator so that the spangles will be properly placed upon the same. As the drive-shaft 27 is rotated, the cam 28 will elevate the multiple punch 3 to cause its member 18 to punch a spangle blank 12 from the metal strip 41. After punch 3 lowers, the mutilated gearing previously described, will cause the dies 1, 2 to make one-half of a revolution, thereby bringing said blank 12 in alinement with the punch 19 and one of the openings 13 in the die 2. The punch 3 is then elevated a second time to cause its member 19 to press said blank into the die 2 and at the same time bend its prongs at right angles. The dies 1, 2, are again given one-half of a revolution, after the punch 3 lowers the second time, and the bent or partially formed spangle in the die 2 is thereby brought beneath the material on which it is to be secured.

Punch 5 now descends, thereby separating the jaws 21 of the spring die 4, so as to be in position to receive the prongs of the spangle. The punch 3 is then elevated again, thereby forcing the prongs of the spangle through the material, between the punch 5 and the jaws 21. Punch 5 is elevated, thereby allowing the jaws 21 to bend the prongs of the spangle inwardly. Punch 3 is withdrawn and the cylinders start to rotate. The spangle and the material to which it is partially secured is now supported on the uninterrupted or plain portion of the cylinder 2. The punch 5 now descends for a second time, clenching the prongs of the spangle against the cylinder 2, as a backing.

While I have described the operation of the machine in forming and attaching but one spangle, it will be understood that the formation of the spangles is continuous and that the latter are fed automatically.

While I have shown and described the preferred embodiment of the invention it will be understood that I do not limit myself to the precise showing set forth, since various changes may be made within the scope of the appended claims.

Having thus described my said invention, what I claim as new and desire to secure by Letters Patent of the United States, is—

1. In a machine of the character set forth, the combination of a plurality of die members having die openings, means for causing the die openings of the said die members

to be placed in register at intervals, and punch members adapted to coöperate with the said die openings to shape the blank and to transfer it from the die opening of 5 one member to the die opening of another member.

2. In a machine of the character set forth, the combination of a plurality of rotatable die members having die openings adapted 10 to be placed in register at intervals, and punch members located interiorly of said

die members adapted to coöperate with the said die openings to shape the blank and to transmit it from the die opening of one member to the die opening of another member. 15

In testimony whereof I hereunto affix my signature in presence of two witnesses.

GEORGE W. BINGHAM.
